UNITED STATES PATENT OFFICE.

HOWARD S. KENNEDY AND CHARLES M. CONNOLLY, OF TROY, NEW YORK, ASSIGNEES,
BY MESNE ASSIGNMENTS, TO CLUETT, PEABODY AND CO., INC., OF TROY, NEW YORK,
A CORPORATION OF NEW YORK.

SHIRT.

Specification of Letters Patent.

Patented Jan. 8, 1918.

Application filed July 3, 1911. Serial No. 636,584.

To all whom it may concern:

Be it known that we, HOWARD S. KENNEDY and CHARLES M. CONNOLLY, each a citizen of the United States, residing at Troy, 5 county of Rensselaer, and State of New York, have invented certain new and useful Improvements in Shirts, of which the following is a specification.

The invention relates to such improvements and consists of the novel construction and combination of parts hereinafter described and subsequently claimed.

Reference may be had to the accompanying drawings, and the reference characters 15 marked thereon, which form a part of this specification. Similar characters refer to similar parts in the several figures therein.

Figure 1 of the drawings is a rear view of an open-front shirt having a pocket in 20 the neckband provided with a buttonhole made in accordance with our invention.

Fig. 2 is a view in perspective of the pocket-portion of the neckband.

The body and neckband of the shirt are 25 shown in a somewhat distorted position for convenience of illustration.

The principal object of the invention is to facilitate the insertion of a stud or collar-button in a wall of a pocket in a garment 30 formed to receive the base of said stud or button.

In laundried articles of apparel, such as shirts, it has been found desirable in order 35 to protect the body of the wearer from contact with the base of a stud or collar-button, to provide the buttonhole-band of the article with a pocket adapted to receive the base 40 of the stud or collar-button, the outer-wall of the pocket being provided with a button-hole through which said stud or button is adapted to be inserted.

As such pockets have been heretofore constructed they ordinarily come from the laundry with the walls of the pocket tightly 45 starched together, rendering access to the buttonhole possible only by pulling open the pocket from bottom to top thereof before the stud or collar-button can be inserted through the buttonhole.

Under such conditions it is usually also 50 found that the walls of the buttonhole are tightly adherent to each other by reason of the accumulation of starch in the buttonhole during the laundrying operation.

In carrying out our invention we are able

to largely avoid such difficulties by making the buttonhole in the form of a notch or open slit extending inward from the outer edge of the outer-wall of the pocket, making it unnecessary for the stud to be inserted within 60 the pocket before it can be inserted through the buttonhole as in constructions heretofore employed.

By the use of our invention, all that is required is to slightly raise the corners of the 65 outer pocket-wall at the mouth of the buttonhole-slit to permit the base of the stud or button to pass thereunder and then to force the stud inward along said slit or notch until it reaches the eyelet-end thereof. 70

Referring to the drawings wherein the invention is shown in preferred form, 1, represents the body of the shirt and, 2, the neckband thereof which opens in front and has its ends secured together by a stud or button, 75 3, inserted through buttonholes formed in the ends of the band in the usual manner.

At the back, where the band is closed, it is formed with a pocket, 4, which may be constructed in any known manner. 80

The outer-wall of the pocket is provided with a notch or slit, 5, which extends inward from the edge of said wall and preferably terminates in an eyelet-end, 6, adapted to freely receive the shank of the stud or collar- 85 button.

In the use of the article so made, the corners of the outer-wall of the pocket adjacent to the slit if adherent, can be slightly raised so as to partly insert the base of the stud or 90 collar-button therebeneath, after which the stud can be forced freely into the pocket, its shank traveling along the slit until it reaches and occupies the eyelet-end, 6.

The stud can be thus inserted if desired 95 after it has been inserted in the collar, which operation is impossible with buttonholes formed in the ordinary manner in the neckband.

In like manner it is unnecessary to remove 100 the stud from the collar in separating the collar from the shirt as the stud can be removed from the pocket by a simple downward pull.

The slit, 5, is preferably made slightly V- 105 shaped or flaring at its mouth to facilitate the entrance of the shank of the stud.

The neckband being attached to the shirt at the back, when the shirt is laundried forms a practically continuous surface com- 110

prising the back wall of the pocket and such extension thereof as is formed by the inner plies of the neckband and the back of the shirt. The continuous surface thus formed serves as a guide for the base of a collar-button along which the latter can be readily slid into the open end of the notch or slit.

It is thus only necessary to force the back part of the collar down over the back of the shirt until the base of the back-stud in the collar is below the neckband of the shirt, and then by pressing inward upon the stud and drawing the back part of the collar upward, the base of the stud can be slid along the continuous surface formed by the back of the shirt and the inner wall of the pocket until the base of the stud is guided into the pocket and the shank of the stud into the notch.

What we claim as new and desire to secure by Letters Patent is—

1. A laundried article of apparel having a stud-pocket with a buttonhole-slit in the outer wall of said pocket extending inward from the edge thereof and adapted to receive the shank of a stud or collar-button inserted in said pocket, the inner wall of said pocket extending beyond the slotted edge of said outer wall.

2. A shirt having a neckband made up of

a plurality of plies of fabric and provided with a stud-pocket formed between certain of its plies, said neckband being provided with a buttonhole-slit in the outer wall of said pocket extending upward from the lower edge thereof and terminating in an eyelet-end adapted to receive the shank of a stud or collar-button inserted in said pocket, the inner wall of said pocket being extended beyond the slotted edge of its outer wall, forming a surface along which the base of the stud can be slid into said slit.

3. A laundried article of apparel having a stud-pocket with a buttonhole-slit in the outer wall of said pocket extending inward from the edge thereof and adapted to receive the shank of a stud or collar-button inserted in said pocket, the inner wall of said pocket and the body of the article of apparel forming a substantially continuous surface extending beyond the slotted edge of said outer wall along which surface the base of the stud can slide in entering the pocket.

In testimony whereof, we have hereunto set our hands this 28th day of June, 1911.

HOWARD S. KENNEDY.
CHARLES M. CONNOLLY.
